[57] **CLAIM**

The ornamental design for a sports racquet string vibration damper, as shown and described.

DESCRIPTION

FIG. 1 is a perspective view of a sports racquet string vibration damper showing my new design, the strings shown in broken lines for illustrative purposes only; FIG. 2 is a front elevational view thereof;

FIG. 3 is a right side elevational view thereof, the opposite side being a mirror image;

FIG. 4 is a top plan view thereof;

FIG. 5 is a bottom plan view thereof; and,

FIG. 6 is a rear elevational view thereof.
